UNITED STATES PATENT OFFICE.

WILLIAM J. SELLECK, OF RIVERSIDE, CONNECTICUT.

APPARATUS FOR UNLOADING, STORING, AND RELOADING MATERIAL.

No. 820,527.

Specification of Letters Patent.

Patented May 15, 1906.

Application filed February 17, 1902. Serial No. 94,564.

To all whom it may concern:

Be it known that I, WILLIAM J. SELLECK, a citizen of the United States, residing at Riverside, county of Fairfield, State of Connecticut, cut, have invented a certain new and useful Improvement in Apparatus for Unloading, Storing, and Reloading Material; and I declare the following to be a full, clear, and exact description of the invention, such as will enable others skilled in the art to which it pertains to make and use the same, reference being had to the accompanying drawings, which form a part of this specification.

My invention relates generally to an apparatus for unloading, storing, and reloading coal, ore, or other material.

At points where coal is unloaded, particularly from vessels, it is desirable that facilities should be provided either for immediately reloading the coal upon cars or for storing it in pockets preparatory to reshipment or for storing it throughout a storage area from which it may be removed and reloaded upon cars, as occasion requires.

The object of my invention is to provide an apparatus for unloading coal from any one of several points or simultaneously from a plurality of points—as, for instance, the hatches of a vessel—and transferring the coal either to any one of a series of pockets or to any desired point in a storage area from which it may be removed and reshipped.

A further object of my invention is to provide an apparatus of the character referred to which will be comparatively simple in construction, practicable in operation, and which will enable coal or other material to be expeditiously and economically handled.

My invention, generally stated, consists in one or more portable towers for removing the coal from the hatches of vessels, a traveling crane projecting above storage-pockets and extending over a storage area, conveying means supported upon the crane for receiving the coal and transporting the same to points above the storage area, and conveying devices also supported from the crane for removing the coal from the storage area and depositing the same in the pockets preparatory to reloading upon cars.

My invention will be more fully described hereinafter with reference to the accompanying drawings, in which the same is illustrated as embodied in two practical and convenient forms, and in which—

Figure 1 is a plan view, principally diagram-

matic, illustrating my invention; Fig. 2, a vertical sectional view taken on line 2 2, Fig. 1, looking in the direction of the arrows; Fig. 3, a cross-sectional view on line 3 3, Fig. 2; Fig. 60 4, a side elevational view of a modified form of my invention, parts being broken away; and Fig. 5 is a front elevational view of the modification shown in Fig. 4 looking from a plane indicated by line 5 5 in the direction of 65 the arrows.

Similar reference characters are used to indicate similar parts in the several figures of the drawings.

Referring more particularly to Figs. 1, 2, 70 and 3, A' indicates a wharf at which vessels are adapted to unload. A designates a vessel provided with hatches a a, through which the vessel is loaded and unloaded. Supported upon tracks b, extending parallel with the 75 wharf, is a plurality of portable towers B', B², B³, and B⁴, each of which comprises uprights B B, extending above the tracks b and connected by any suitable struts to impart the necessary strength to the towers. The structure of said towers is well known and need not be described in detail. Each tower is provided with an arm b², extending above the vessel to be unloaded, and supported at its end opposite the tower by any suitable means 85 b⁶. A trolley b³ is supported upon the arm b² and may be propelled thereon so as to secure the desired position above the vessel. A bucket b⁴, preferably of the clam-shell type, depends from the trolley b³ and may be lowered through the hatch of a vessel filled with coal and elevated in a manner well known in the art. The trolley conveys the loaded bucket b⁴ to a point above a chute b⁵, which is carried by the tower. A series of pockets C 95 are supported parallel with and adjacent to the tracks b for the towers by any suitable means, as a substructure c. The lowest point in the pockets C is slightly above the tops of or doors in cars F, which run upon tracks f f, 100 located between the rails of the tracks b, upon which the towers travel. Ties C² extend transversely across the pockets C and support a track c', which extends parallel with and near to the front edge of the pockets and below the discharge-point of the chute b⁵ of each of the towers. The track c' curves at the opposite ends of the series of pockets, as indicated at the bottom of Fig. 1, and returns at a lower level than the tops of the pockets, as indicated in Fig. 2, such return-track being sup-

substructure *c* of the chutes. Supported upon the cross-ties *C*² above the pockets *C* between the track *c'* and the edge of the pockets farthest from the towers are parallel tracks *c'*², upon which are supported the ends of traveling cranes *D* *D*. The traveling cranes extend over and above a storage area and are supported at their rear ends upon a track *e'* by means of upright truss-supports *D*³, having wheels *D*⁴ engaging the track *e'*.

Each of the cranes is preferably T-shaped, so that the portion *D'* thereof above the pockets *C* extends along the tracks *C*² a distance equal to the distance between the outer edges of two or more hatches of a vessel. In Fig. 1 the portion *D'* of the crane above the pockets is shown as extending opposite four hatches of the vessel *A*. The portion *D*² of each crane, which connects the extended portion *D* thereof and the truss-support *D*³, is connected in any suitable manner to give the desired strength and rigidity to the structure. In Fig. 3 the portion *D*² of each crane is shown as comprising uprights *d* *d'*, connected at their tops by cross-ties *d* and connected at their lower ends to cross-ties *d*², cross-struts *d*³ being also shown to add strength to the structure. An endless track *e* depends from the cross-ties *d*² by means of hangers *d*⁵. The track *e* is located below and around the outer edge of both portions *D'* and *D*² of the crane *D* and extends above and parallel with the track *c'* above the pockets *C*. Cars *E* are supported by and depend from the endless track *e* and are propelled by any suitable means—as, for instance, a cable *G*. A track *e'* also depends from the cross-ties *d*² and extends centrally below the crane from a point above the pockets to the rear of the crane. A pick-up *E'* is supported by the track *e'* by means of a trolley *e*², which may be propelled in any well-known manner. The construction and operation of the pick-up is common in the art and need not be further described in detail.

The operation of the embodiment of my apparatus illustrated in Figs. 1, 2, and 3 is as follows: The towers *B'*, &c., are moved along the track by any suitable propelling means to points opposite the hatches of a vessel *A*. The width of the towers is such as to permit them to be located opposite adjacent hatches. The cranes *D* are then propelled by any suitable motive means to points opposite the towers. The buckets *b*⁴ are then operated to remove the coal or other material through the hatches of the vessel and dump the same above the chutes *b*⁵ of the towers. The coal passes through the chutes either directly into the pockets *C* and thence into cars *F*, or it may be received by the cars *E*², which are supported upon the track *c'* above the pockets *C* and beneath the discharging ends of the chutes and conveyed by such cars to points above the various chutes in the series remote

from the point where the coal is being unloaded, thereby enabling all of the pockets in the series to be filled with coal conveyed to them from the point where the vessel is being unloaded. The return portion of the tracks *c'* is supported at a lower level, as indicated in Fig. 2, so that the empty cars will pass beneath the paths of movement of the cars *E* and pick-up *E'*. The coal passing from the chutes *b*⁵ may also be received by the cars *E*, depending from the endless track *e*, and conveyed by them to points above the storage-space between the opposite ends of the traveling cranes and dumped. When it is desired to remove the coal from the storage-space, the pick-ups *E'* are operated, which convey the coal from the storage area to points above the pockets, where they are dumped, thereby depositing the coal in the pockets ready for reshipment.

In Figs. 4 and 5 I have illustrated a modified form of traveling crane in which the extended end adjacent to the towers projects downwardly and is supported upon tracks *d*⁶, located upon the same horizontal plane as the tracks *e* of the towers. The structure which is interposed between the tracks *d*⁶ and the upper portion of the crane may be of any desired form, for convenience it being shown as comprising converging struts *d*⁵ *d*⁶, which are connected to a beam *D*⁶, beneath which are the wheels engaging the tracks *d*⁶. Supported within the substructure of the crane are pockets *C*⁴, located at a level to discharge into the cars *F*, which run upon tracks *f*, located between the rails *b* of the track upon which the towers are supported. In this modification of my invention no stationary pockets are employed, and consequently the track *c'* and cars engaging the same are omitted. The crane, however, is, as in the previously-described embodiment of my invention, provided with an endless track *e*, supporting cars *E*, and a track *e'*, supporting pick-up buckets *E'*. The operation of this embodiment of my invention differs from that previously described only in that the pockets *C*⁴ are carried along by the cranes and receive the coal either directly from the discharging end of the chutes *b*⁵ or from the pick-ups *E'* when the coal is being removed from the storage-space. The coal which is being unloaded from the vessel may discharge either directly into the pockets *C*⁴ or into the cars *E*, and be conveyed by them to points above the storage area and there dumped.

From the foregoing description, it will be observed that I have invented an apparatus capable of simultaneously unloading coal through a plurality of hatches on a vessel and conveying the same either to various pockets remote from the vessel or to points above a storage-space, from which it may be removed, when desired, for reshipment. It will also be observed that the towers may be located ad-

adjacent to any of the hatches and that each of the cranes is capable of receiving the coal from any one of several adjacent hatches.

While I have described more or less precisely the details of construction, I do not wish to be understood as limiting myself thereto, as I contemplate changes in form, the proportion of parts, and the substitution of equivalents as circumstances may suggest or render expedient without departing from the spirit of my invention.

Having now fully described my invention, what I claim as new, and desire to secure by Letters Patent, is—

15. 1. In an apparatus of the character described, the combination with movable unloading mechanism, of a series of pockets, located adjacent to the path of movement of the movable unloading mechanism; and conveying means located above and extending longitudinally with respect to said pockets for receiving said material directly from the unloading mechanism, carrying the same to points above the pockets and depositing it in any desired pocket.

2. In an apparatus of the character described, the combination with movable unloading mechanism, of a series of stationary pockets, a track supported longitudinally above said pockets, located adjacent to the path of movement of the movable unloading mechanism; and cars engaging said track for receiving material directly from the unloading mechanism, conveying the same to points above the pockets and depositing it in any desired pocket.

3. The combination with a vessel, of a plurality of movable towers each carrying unloading mechanism, a series of stationary pockets located adjacent and parallel to the path of movement of the towers, a track supported longitudinally above said pockets, and cars engaging said track for receiving material directly from the towers, conveying the same to points above the pockets and depositing it in any desired pocket.

4. In an apparatus of the character described, the combination with a plurality of unloading mechanisms, of a traveling crane having an extended portion adapted to be located parallel with and opposite said plurality of unloading mechanisms and extending over a storage area, and conveying means supported upon said crane for receiving material from said plurality of unloading mechanisms and carrying the same to points above the storage area.

5. In an apparatus of the character described, the combination with unloading mechanism, comprising a trolley, a bucket depending from the trolley and hoisting means for the bucket, of a pocket located adjacent thereto, a traveling crane extending from a point above said pocket over a storage area, and conveying means supported

upon said crane for receiving material from the unloading mechanism and carrying the same to points above the storage area.

6. In an apparatus of the character described, the combination with unloading mechanism, of pockets located adjacent thereto, a traveling crane extending from a point above said pockets over a storage area, conveying means supported upon said crane for receiving material from the unloading mechanism and carrying the same to points above the storage area, and conveying means located above said pockets for receiving material from said unloading mechanism and carrying the same to points above the pockets.

7. In an apparatus of the character described, the combination with movable unloading mechanism, of a series of stationary pockets, a track supported above said pockets, cars engaging said tracks for receiving material from the unloading mechanism and conveying the same to points above the pockets, a traveling crane extending from a point above said pockets over a storage area, and conveying means supported upon said crane for receiving material from the unloading mechanism and carrying the same to points above the storage area.

8. The combination with a plurality of towers each provided with unloading mechanism, of a traveling crane having an extended portion adapted to be located parallel with and opposite said plurality of towers, said crane projecting over a storage area, and conveying means supported upon said crane for receiving material from said plurality of towers and carrying the same to points above the storage area.

9. The combination with a vessel having a plurality of hatches, of a plurality of movable towers provided with unloading mechanism and adapted to be located opposite said plurality of hatches, a traveling crane having an extended portion adapted to be located parallel with said vessel and opposite said plurality of towers, said crane projecting over a storage area, and conveying means supported by said crane for receiving material from said plurality of towers and carrying the material to points above the storage area.

10. The combination with a plurality of movable towers each provided with unloading mechanism, of a series of stationary pockets located adjacent and parallel with the path of movement of said towers, a traveling crane having an extended portion supported above said pockets and located opposite said plurality of towers, said crane projecting over a storage area, and conveying means supported by said crane for receiving material from said plurality of towers and carrying the material to points above the storage area.

11. The combination with a plurality of movable towers each provided with unloading

- ing mechanism, of a series of stationary pockets located adjacent and parallel with the path of movement of said towers, conveying means located above said pockets for receiving material from said towers and carrying the same to points above the pockets, a traveling crane having an extended portion supported above said pockets and located opposite said plurality of towers, said crane projecting over a storage area, and conveying means supported by said crane for receiving material from said plurality of towers and carrying the material to points above the storage area.
12. The combination with a vessel having a plurality of hatches, of a plurality of movable towers each provided with unloading mechanism and adapted to be located opposite said plurality of hatches, a series of stationary pockets located adjacent to and parallel with the path of movement of said towers, conveying means located above said pockets for receiving material from said plurality of towers and carrying the same to points above the pockets, a traveling crane having an extended portion supported above said pockets and adapted to be located opposite said plurality of towers, said crane projecting over a storage area, and conveying means supported upon said crane for receiving material from said plurality of towers and
- carrying the material to points above the storage area.
13. In an apparatus of the character described in combination, a movable unloading tower, a bridge movable independently of said unloading tower, a continuous loop-track extending across said bridge and into proximity with said tower, and an endless traction-cable for said loop-track.
14. In an apparatus of the character described, the combination with a storage area, of a movable unloading-tower, a continuous loop-track extending into proximity with said tower, and a movable bridge upon which said track is supported above the storage area.
15. In an apparatus of the character described, the combination with a storage area, of a continuous loop-track comprising a transverse portion above said area and a longitudinal portion, an unloading-tower located adjacent and movable with respect to the longitudinal portion of said track, and a movable bridge extending across said area upon which the transverse portion of said track is supported.

In testimony whereof I sign this specification in the presence of two witnesses:

WILLIAM J. SELLECK.
